UNITED STATES PATENT OFFICE

93,770

DESIGN FOR AN ELECTRIC INSECT EXTERMINATOR

Harry Israel, Dayton, and Alexander H. Roehr,
near Dayton, Ohio

Application March 2, 1934, Serial No. 50,927

Term of patent 3½ years

To all whom it may concern:

Be it known that we, HARRY ISRAEL and ALEXANDER H. ROEHR, citizens of the United States, and residents, respectively, of the city of Dayton, county of Montgomery and State of Ohio, and of the county of Montgomery, near the city of Dayton and State of Ohio, have invented a new, original, and ornamental Design for an Electric Insect Exterminator, of which the following is a speci-

fication, reference being had to the accompanying drawing, forming part hereof.

The figure is a perspective view of an electric insect exterminator, showing our new design.

We claim:

The ornamental design for an electric insect exterminator, as shown.

HARRY ISRAEL.

ALEXANDER H. ROEHR.
